Primary Examiner — Darlington Ly*Assistant Examiner* — D. Ryan Tisdale(74) *Attorney, Agent, or Firm* — Smyrski Patent Law, PC(57) **CLAIM**

The ornamental design for an automotive front splitter, as shown and described.

DESCRIPTION

FIG. 1 is a top, front and left side perspective view of an automotive front splitter embodying my new design as installed on an environmental automobile;

FIG. 2 is a top, front and left side perspective view of the standalone automotive front splitter;

FIG. 3 is a bottom, rear and right side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines in the drawings illustrate portions of the automotive front splitter, as well as environment, that form no part of the claimed design.

1 Claim, 7 Drawing Sheets(56)
